LEVER HANDLE

Leo J. Maffei, New Britain, Conn., assignor to The American Hardware Corporation, New Britain, Conn., a corporation of Connecticut

Filed Oct. 16, 1962, Ser. No. 72,127

Term of patent 14 years

(Cl. D10—8)

FIG. 1 is an isometric view illustrating the lever handle embodying my new design.

FIG. 2 is a top elevational view of said lever handle, but on a smaller scale than FIG. 1.

FIG. 3 is a front elevational view of the lever handle shown in FIG. 2.

FIG. 4 is an end elevational view of said lever handle.

FIGS. 5 to 9 are sectional end views of said lever handle taken, respectively, on lines 5—5 to 9—9 of FIG. 3.

The dominant features of my new design reside in the portions shown in solid lines.

I claim:

The ornamental design for a lever handle, substantially as shown and described.
